REPLACEABLE SASH AND FRAME FOR SAME

Pasquale De Pietro, Woodmere, N. Y.

Application November 27, 1935, Serial No. 51,730

14 Claims. (Cl. 20—55)

My invention concerns sashes and window frames.

One object of my invention is to provide sashes which may be readily removed from a window frame for purposes of replacement, cleaning or repairing. My invention is therefore particularly useful in connection with sashes for screen and storm windows which are seasonally replaced.

10 A further object of my invention is to provide means on a sliding sash which retain said sash in the allocated position while it is slid up and down in the frame, but which still allows the removal of the sash from the window without 15 difficult mechanical operation.

Another object of my invention is to provide 20 sliding window sashes which may be slid up and down in a suitable window frame to substantially the full extent thereof, while in use; which 25 however, can readily be removed from the frame.

It is also an object of my invention to provide, in combination with light window sashes which can readily be removed from a window frame, means which securely retain said sashes 25 at any level of their sliding range without necessitating the use of counterweights.

A further object of my invention is to provide a rugged, strong and simple structure for attaining the objects of this invention. I also 30 provide a window frame for replaceable sashes which may be superimposed upon a window, in the casing thereof.

Other objects will be revealed in and become 35 more clear from the following description and from the accompanying drawings, in which

Fig. 1 shows the perspective front view in elevation of a window frame in which sliding sashes are assembled.

Fig. 2 shows a vertical transverse section of 40 the frame.

Fig. 3 shows a sectioned detail plan view of the frame, and of the partly sectioned sashes assembled therein, taken on the line 3—3 of Fig. 1.

45 Fig. 4 shows a sectional, horizontal section, taken on the line 4—4 of Fig. 2; the sashes being removed from the frame.

Fig. 5 shows, in a view similar to that of Fig. 3, a modified form of my invention.

50 Fig. 6 shows from the inside an elevation of a modification of the novel frame and sashes of my invention. A section of the top rail of the frame and the right sides of the sashes are broken away.

55 Fig. 7, and Figs. 8 and 9 show corresponding

side views of the top sash and of the bottom sash and frame, respectively, the two latter being cross-sectioned, the frame of Fig. 9 being positioned in a window casing and the sashes of Figs. 7 and 8 being transversely exploded from said frame.

Similar numerals refer to similar parts throughout the various views.

The window frame shown in Fig. 1 is to be mounted in a window casing, e. g. superimposed 10 from the outside upon the ordinary window in said casing. The sides 6 and 7, the top 8 and the base 9 of said frame are rectangularly assembled behind the outer lining 10 of the frame, said lining being for instance flashed onto the 15 outer face of said casing (not shown). In its side view (Fig. 2) said frame faces outward to the left, inward to the right.

A tongue 11 extends around the inside of the lower part of the frame and is mounted upon 20 the inside of the sides 6 and 7 and of the base 9 of said frame. A tongue 11 fits into a groove 12 which extends around the lower sash 13 in the stiles 14 and 15, and in the lower rail 16 of said sash. A tongue 17 extends from the inside of 25 the upper part of the frame in a manner equivalent to that in which the tongue 11 is arranged in the lower part of the frame, but it is outwardly offset in respect to the tongue 11, so that the upper sash 18, which engages upon said 30 tongue by means of a groove 19 extending around the stiles 20 and the upper rail 21 of said sash operates in the outward half of the frame substantially parallel to the lower sash 13, which operates substantially in the inward half of the 35 frame.

The tongues 11 and 17 are provided with flanges 22 which rectangularly extend from said tongues and by means of which said tongues are fastened upon the inner walls of the frame. The 40 parts of the flanges 22, which are mounted upon the sides 6 and 7 of the frame, are provided with regularly spaced clearances, through which protrude the center parts of the flat springs 23 into frictional engagement upon the stiles of the 45 sashes 13 and 18, the free ends of said flat springs being slidably retained below said flanges 22 in suitable grooves in the sides 6 and 7 of the frame. In the sashes 13 and 18 are mounted window panes 24 or screens 25, and upon the rails of 50 the sashes are mounted handles or lifts 26 which facilitate the operation of the sashes.

Upon the upper rails 27 and 28 of the two sashes 13 and 18, are mounted horizontal rods 29 which extend from both sides of said sashes 55

into suitable grooves or runways 29 and 30 in the frame, respectively. The free ends of the rods may either fit these grooves, as indicated in Fig. 5, or they may carry rollers 31 of such diameter that they fit the width of said grooves, as indicated in Figs. 1 and 3. The runways 29 and 30 are connected at their lower ends, at the center of the frame, by a transverse groove 32, which opens at the front of the frame from the 10 inside face thereof.

From a slit in the top 8 of the frame hingedly depends a latch 33 which serves as a stop for the inner, lower sash 13, when said sash is slid in the frame. When that latch is swung around its 15 fulcrum into a horizontal position, it clears the inside of the frame, so that the lower sash may be fully slid up in said frame. When the lower sash is thus slid all the way up in the frame, the grooves 12 in the stiles 14 and 15 of said sash 20 are disengaged from the tongue 11; whereas said grooves are still engaged on said tongue, when the upper rail 27 of the lower sash 13 strikes the lower end of the latch 33 in its depending, vertical position. When the latch 33 25 is in a horizontal position, and the lower sash 13 is slid all the way up in the frame, as described before, so that said sash is not engaged upon the tongue 11 any more, the lower end of the lower sash may be pulled inwardly out of the frame, 30 the upper end of the sash being still engaged upon the frame because the free ends of the rods 28, or the rollers 31, which are journalled upon said free ends, are still engaged in the runways 29. When the lower end of the lower sash is 35 thus withdrawn from the frame, the sash swings around the rods 28 and may be swung around these fulcrums into a substantially horizontal position. If the lower sash is then lowered, while extended in a horizontal position, the free ends 40 of the rods 28 or the rollers 31 slide or roll down in the runways 29 into the groove 32. When the free ends of the rods, or the rollers are in the groove 32, the sash may be withdrawn from the window frame, since said groove 32 opens inwardly from the frame. It is thus seen that the 45 free ends of the rods 28 or the rollers 31 guide the upper end of the lower sash along the vertical track of the runways 29 as long as the lower sash is in the window, and these free ends of the 50 rods or rollers aid the tongue 11,—which, as such, guides the sash only in the lower part of the frame,—in securely slidably retaining the lower sash along its whole range of movement in the frame. The lower sash is therefore guided 55 in the frame along its whole length at all times, except when it is raised to its very highest position.

To the extent to which the upper rail 27 of the lower sash 13 and the lower rail 34 of the 60 upper sash 18 vertically overlap each other, they are provided with horizontally overlapping strips 35, (the strip on the rail 34 does not show in the drawings) which serve to close the space between said sashes, when said sashes are in the 65 fully closed position of Fig. 1. Such strips are of course not necessary when the sashes themselves are in sliding abutment upon each other in the frame. But the friction of the sashes upon each other, while sliding up and down in 70 the frame, is reduced, if the only places of abutment are the strips 35.

The upper sash 18 is slideable upon the tongue 17, when it is in the upper part of the frame, whereas said sash is vertically guided, when it 75 is in the lower part of the frame, outwardly by

the outer lining 10 of the frame, and inwardly by the lower sash 13.

After the lower sash 13 has been removed from the frame, the upper sash may be removed from the frame in the following manner:—

It is slid into its lowest position, the rod 28 or the roller 31 of said rod travelling along the runway 30, until it drops into the groove 32, when said sash has reached its lowest position. Since the lower sash has provisionally been removed 10 from the frame, the upper sash can now be moved along the groove 32 into the runway 29. The upper sash is now lifted up to its highest position, the rod 28 on the upper end thereof, or the rollers 31 on said rods, travelling along 15 the runway 29. When the rod 28 or the roller 31 is at the upper end of the runway 29, the lower end of the upper frame 18 may be swung inwardly above the tongue 11, into a vertical position, the rod 28 serving as a fulcrum around 20 which the sash is swung. The upper sash 18 can now be removed from the frame in the same manner the lower sash has been removed before, i. e., the sash is lowered in a horizontal position, the rods 28 or the rollers 31 travelling 25 along the runway 29, until they finally are withdrawn from the frame through the groove 32 at the lower end of the runway 29.

The sashes 13 and 18 (storm windows), or substitute sashes, (e. g. screens), are reintroduced or introduced into the frame by a reversal of the above-described procedure of removal.

It is understood that my device may be constructed in a great number of modifications; reversing the arrangement of tongues and 35 grooves on the frame and on the sashes would be one such modification.

In the modification of Fig. 5 the insides of the frames are substantially completely covered with sheet metal, the tongues 11 and 17 being produced by folds in said sheet metal. The sheet metal serves also as a lining in the runways for the free end of the rod 28, or the roller 31, thus providing a smooth surface for the sliding or rolling action of those parts, and at the same 45 time strengthening the surfaces which are subjected to wear and tear.

The modification of Figs. 6, 7, 8 and 9 shows my invention in a very simple form.

The frame 51 extends around only three sides 50 of my replacement window, and consists therefore of the sides or stile runways 52 and 53 and the top piece or connecting member 54. This frame is inserted from the outside in a window casing and suitably fastened in position. The 55 sill remains clear (Fig. 9).

In Fig. 9 I face the window casing 55 from the left. Upon the inside, inwardly, is the window proper 56. From the outside the frame 51 is inserted, the lining 10 abutting for instance upon the outer face of the casing 55, whereas the rest of the frame extends into said casing. The sides 52 and 53 rest directly upon the sill 57 of the casing 55, so that the lower sash, provided with a weather strip is preferred (not shown), closes 65 directly upon the sill 57. Thus any water caught between my replacement window and the window proper 56, may drain outwardly over the sill 57.

A rim or staffhead 58 extends around the inside 70 on the three sides of the frame, in alignment with the outward face thereof. This rim 58 extends alongside of the upper sash 59 (a screen in this case) and retains it in its fully lowered position in the frame in one outward direction; 75

but a groove 61 extends around three sides of said sash, and slidably fits over the tongue 62, which extends around the upper sides 52 and 53 and the top piece 54, upon the inside of the frame.

5 In a corresponding manner, grooves (not shown) extend in two opposite sides of the lower sash 60, and they are guided by the tongues 63, which are arranged upon the inside of the sides 52 and 53, at and near the lower end thereof.

10 In the manner described hereinbefore in respect to the other modifications, the guides 62 and 63 are transversely offset in relation to each other, the guide tongues 62 being arranged outwardly, and the guide tongues 63 being arranged inwardly, said tongues being relatively offset substantially to the extent of the thickness of the sashes.

Therefore the sashes 59 and 60, as shown in a dot-dash line in Fig. 9 in a closed position, overlap in abutment upon each other. In its top position sash 59 is guided by tongue 62; in its bottom position between rim 58 and sash 60.

If the lower sash 60 is to be removed from the window, it is simply raised and taken out in an inward direction. In order to avoid that sash 60 drops out inwardly when raised, I prevent the said sash from being lifted to the highest position at which it is slid from tongues 63, again providing a latch 33, in analogy to the arrangement shown in Fig. 1 etc.

30 The upper sash 59 cannot be removed when the lower sash 60 is in the window. After the lower sash 60 has been removed from the window, I may remove the upper sash 59 by pulling it way down, until it has disengaged from the tongue 62 and then it may be removed, by being lifted out at an angle through the space or gap between the tongues 62 and 63.

35 The tongues 62 and 63 may have the shape of angles, so that they are mounted by way of one leg of such angular profile upon the inside of the frame, or are sunk thereinto, as shown in the drawings.

Instead of providing tension means in the frame, as they were shown in the other figures, 40 I show the tension means in the modification of Figs. 6, 7, 8 and 9, to be arranged upon the sashes themselves. One or more flat springs 23 are superimposed on the sides of the sashes, so to speak. In reality they are sunk into the grooves 45 upon the sides of the upper and lower sashes, being flush with the bottoms of said grooves when depressed, their curved center parts bulging normally up onto said grooves, thus frictionally engaging the tongues 62 and 63, respectively.

50 While I have shown and described my invention with some degree of particularity, it will be realized that other modifications and changes may be resorted to under special conditions. I 55 therefore do not wish to be limited and restricted to the exact details shown and described, but reserve the right to make such changes and modifications as may fairly fall within the scope of the subject matter now being claimed.

60 What I claim is:

1. In combination with the upper and the lower sash of a sliding window, a frame upon which said sliding sashes are tensionally engaged, and round guide means laterally extending from one 65 end of said sashes into runways in said frame, said runways opening at one point frontwardly through said frame.

2. In combination with the upper and the lower sash of a sliding window, a frame upon which said 70 sliding sashes are tensionally engaged, and round

guide means laterally extending from the upper ends of said sashes into runways in said frame.

3. In combination with the upper and the lower sash of a sliding window, a frame, tongues laterally extending from said frame and slidably engaged upon the stiles of said sashes, and round guide means laterally extending from one end of said sashes into runways in said frame, said runways opening at one point frontwardly through said frame.

4. In combination with the upper and the lower sash of a sliding window, a frame, tongues laterally extending from the upper and the lower part of said frame and slidably engaged upon the stiles of said upper and lower sashes, respectively, and round guide means laterally extending from one end of said sashes into runways in said frame, said runways opening at one point frontwardly through said frame.

5. In combination with the upper and the lower sash of a sliding window, a frame, tongues laterally extending from the upper and the lower part of said frame and slidably engaged upon the stiles of said upper and lower sashes, respectively, and round guide means laterally extending from said sashes into runways which are arranged in said frame alongside of only those of said tongues which extend from the upper part of said frame.

6. In combination with the upper and the lower sash of a sliding window, a frame, tongues on said frame slidably engaging said sashes, and round guide means laterally extending from said sashes into vertically disposed runways in said frame, and transverse grooves opening from said runways through said frame.

7. In combination with a sash in a window frame, means slidably supporting said sash in said frame, and a stop mounted in said frame and preventing said sash from being slid to one extreme position in said frame, said sash sliding off said supporting means, when said stop is removed and when said sash is slid into the respective extreme position in said frame.

8. In combination with a sash in a window frame, means slidably supporting said sash in said frame, auxiliary means guiding one end of said sash in said frame, and a stop mounted in said frame and preventing said sash from being slid to one extreme position in said frame, said sash sliding off said supporting means, when said stop is removed and said sash is slid into the respective extreme position in said frame.

9. In combination with upper and lower sashes of a window frame, a sheet covering on said frame bent to form profiles with tongues and grooves on the inner faces of said frame, and protruding parts and recesses on said sashes slidably engaged on said profile, said profile being interrupted at one point of the extent thereof, and clearing one 60 of said protruding parts frontwardly in order to facilitate removal of said sash from said frame.

10. In a window frame, an upper and a lower sash, upper and lower sets of tongues in said frame serving as stile runways for said upper and lower sash, respectively, and a staffhead forming a part of said frame extending around three sides of said frame and retaining said upper sash in abutment upon said lower sash, when said upper sash is in a lowered position and has been slid off 70 the respective upper set of tongues.

11. In a window frame, an upper and a lower sash, sets of tongues extending partways down and up in said frame and serving as stile runways for said sashes, respectively, and a staffhead ar- 75

ranged on opposite sides of said frame and guiding said upper sash when it is lowered.

12. In combination with a window casing a window frame, an upper and a lower sash, sets of tongues forming part of said frame extending partways down and up in said frame and serving as stile runways for said sashes, respectively, and flat springs arranged in recesses of said sashes and slidably engaged upon said tongues.

13. In combination with a window casing a window frame, an upper and a lower sash, sets of tongues forming part of said frame extending partways down and up in said frame and en-

gaged in grooves in and serving as stile runways for said sashes, respectively, and flat springs arranged in recesses set back in the grooves of said sashes and slidably engaged upon said tongues.

14. In combination with a window casing a window frame, an upper and a lower sash, sets of tongues forming part of said frame extending partways down and up in said frame and engaged in grooves in and serving as stile runways for said sashes, respectively, and flat springs arranged in recesses set back in the bottoms of the grooves of said sashes and slidably engaged upon said tongues.

PASQUALE DE PIETRO.
